PLANT STAKE

Dennis Michael Bartels, Leawood, Kans., assignor to Mid-West Enterprises, Inc., Leawood, Kans.

Filed Dec. 30, 1971, Ser. No. 214,503

Term of patent 14 years

Int. Cl. D31—00

U.S. Cl. D35—1

FIG. 1 is a front elevational view of one embodiment of a plant stake showing my new design;

FIG. 2 is a side elevational view thereof;

FIG. 3 is a top plan view;

FIG. 4 is an enlarged side elevational view opposite that shown in FIG. 2;

FIG. 5 is a bottom plan view;

FIG. 6 is a rear elevational view; and

FIG. 7 is a sectional view taken on line 7—7 of FIG. 6.

I claim:

The ornamental design for a plant stake, substantially as shown and described.
